UNITED STATES PATENT OFFICE.

STANISLAS BEAUREGARD, OF ST. HENRI, CANADA, ASSIGNOR TO JOSEPH ADAM, OF MONTREAL, CANADA.

NAIL-MAKING MACHINE.

SPECIFICATION forming part of Letters Patent No. 739,976, dated September 29, 1903.

Application filed August 12, 1901. Renewed February 21, 1903. Serial No. 144,526. (No model.)

To all whom it may concern:

Be it known that I, STANISLAS BEAUREGARD, a subject of His Majesty the King of Great Britain, residing at St. Henri, county of Hochelaga, Province of Quebec, Canada, have invented certain new and useful Improvements in Nail-Making Machines; and I do hereby declare that the following is a full, clear, and exact description of the invention, such as will enable others skilled in the art to which it appertains to make and use the same.

My invention relates to improvements in nail-making machines, the same being more particularly directed to that class of machines which produce from a continuous length of wire a "string" or a connected strip of nails or tacks which are intended for use in hand lasting-tools by persons engaged in shoe manufacture, although the product of the machine may be used for other purposes.

The primary object of this invention is to simplify the construction of machines of this class and to increase the speed of the working parts, thereby increasing the productive capacity of the machine.

Further objects and advantages of the invention will appear in the course of the subjoined description, and the novelty in the combination and construction of parts will be defined by the claims.

In the accompanying drawings, forming a part of this specification, Figure 1 is a plan view of a nail-making machine embodying my invention. Fig. 2 is a vertical longitudinal section thereof in the plane of the dotted line 2' 2 on Fig. 1 looking in the direction of the arrow. Fig. 3 is a vertical transverse section in the plane of the dotted line 3 3 on Fig. 1, also looking in the direction of the arrow. Fig. 4 is another vertical transverse section taken in the irregular plane indicated by the dotted line 4 4 on Fig. 2 looking in the direction of the arrow. Fig. 5 is another transverse section taken in the irregular plane indicated by the dotted line 5 5 on Fig. 2 and looking in the direction of the arrow. Fig. 6 is an enlarged detail vertical section in the plane of the dotted line 6 6 on Fig. 5. Fig. 7 is a detail perspective view of the feeder-lever removed from the machine. Figs. 8, 9, and 10 are sectional plan views through

the two sets of dies, illustrating the different positions of the dies in the process of pointing and heading the nails in a continuous strip or string. Fig. 11 is a detail perspective view of the lever which moves one of the set of gripper-dies.

The same numerals of reference denote like parts in each of the several figures of the drawings.

5 designates the supporting-stand, which is furnished with the yoke 6, the latter being equipped with the shaft-bearings 7, upon which is secured the bed-plate 8. The shaft-bearings are arranged in alinement to accommodate the single main shaft 9, the latter being provided with the fast and loose pulleys 10 11 and with the balance-wheel 12. From one corner of the bed 8 extends the arm 13, on which is revolubly mounted the wire-reel 14. (See Fig. 1.) To the other end of the bed-plate is secured the outwardly-extending bracket 15, which supports the shaft or arbor 16 of the take-up reel 17, the latter being provided with a belt-pulley 18, around which passes the crossed belt 19, that is driven from the pulley 20. Said pulley is made fast with the counter-shaft 21, which is provided with a worm-wheel 22, that has intermeshing engagement with a worm 23 on one end of the main shaft 9, whereby the take-up reel is driven at slow speed through the intermediate gearing connecting the same with the main shaft.

24 designates a plate which is attached to a short vertical post 25, that is secured upon the bed 8, near one end of the latter, and this plate 24 supports the wire-guide 26 and the series of straightener-rolls 27. The wire from the reel 14 passes through the guide 26 and between the straightener-rolls, thereby taking the "kink" out of the wire and preparing it for reception by the feed mechanism. This feed mechanism comprises a lever 28, which is arranged in a vertical position in the slot 29 of the bed-plate. A die-supporting block 30 is secured firmly upon the bed-plate and is provided with a slot 31, which is coincident with the slot 29, (see Fig. 2,) and through these slots passes said feeder-lever 28. The feeder-lever is fulcrumed at a point intermediate of its length by a bolt or arbor 32, which

is secured in the die-supporting block 30, and the lower end of said lever is provided with a trundle-roller 33, the same being revoluble in a horizontal plane and on the vertical axis 5 afforded by said lever. The trundle-roller rides against the lateral active face of the feeder-cam 34, which is secured to the shaft 9 at a point directly below the slot 29 in the bed, and this cam is effective to impart the 10 vibratory motion to the feeder-lever 28 in order to advance the wire through the dies at the proper intervals. The feeder-lever is provided at a point above the die-block 30 with a plate or arm 35, upon which the wire is 15 adapted to rest after it passes between the straightener-rolls. A feed-finger 36 is mounted by a rocking arbor 37 on the feeder-lever in a position for the pointed end of said feed-finger to lie in co-operative relation to the 20 feed plate or arm 45. The rocking arbor 37 passes through the feeder-lever 28, as shown by Fig. 7, and it is provided with a pin 38, to which is attached one end of a coiled spring 39, the latter being fastened to the lever, also 25 as shown by Fig. 7, said spring serving to normally hold the feed-finger 36 in a position to grip the wire between its pointed end and the feed-plate 35.

My machine is equipped with two sets of 30 dies, one of which sets of dies consists of the pair or members 40 41, while the other set of dies is comprised in the members 42 43. (See Figs. 3, 4, 8, 9, and 10.)

The dies 40 41 constitute the pair of gripping-dies, and they are mounted in the up-standing member 30^a of the die-block 30. This member of the die-block is provided with a horizontal slot, which opens through one edge of said member and which is formed 35 with a guideway 44. The gripper-die 40 is fitted in the guideway, so as to be held adjustably therein by the screws 45 46, thus making the die 40 normally occupy a stationary relation to the companion gripper-die 41, the latter being slidably confined in the die-block member 30^a. This movable gripper-die 41 extends beyond the edge of the die-block 30, so that it may be formed with a notch that terminates in a shoulder 47, and with this shoulder 45 engages the hooked end of a retractor-plate 48. (See Figs. 3 and 11.) The retractor-plate is slotted, as at 49, and is fitted upon the headed upper end 50 of an actuating-lever 51, said retractor-plate being adjustably secured 50 to the lever by means of a screw 52 or its equivalent. The lever is furthermore provided with an adjusting-screw 53, which is arranged to impinge the end of the movable gripper-die 41, as shown by Fig. 3, and the retractor-plate 55 60 and the screw serve to connect the die 41 operatively with the lever 51, whereby said gripper-die is positively moved with relation to the stationary companion gripper-die 40. The lever 51 is fulcrumed at a point intermediate of its length, as at 54, on a suitable part of the bed 8 or the die-block 30, and the lower end of this lever 51 is furnished with a trun-

kle-roller 55, said lever 51 being bent at a point intermediate of its length, as shown more clearly by Figs. 2 and 11. The trundle-roller 55 is thus brought into operative relation to the periphery of the gripper-actuating cam 56, the latter being secured to the main shaft 9 at a point adjacent to the feeder-actuating cam 34, (see Fig. 2,) thus making provision for positively actuating the lever 51 in order to open and close the gripper-dies 40 41 at the proper interval.

The vertical member 30^a of the die-block is provided with a passage 57 and with a guide 58, as shown by Fig. 2, thus making provision for the passage of the wire from the feeder through the passage and the guide to the co-operating faces of the set of gripper-dies 40 41.

The peculiarity of my invention resides in the set of pointing-dies 42 43 and the means for actuating the same. These dies 42 43 have the opposing faces thereof beveled or inclined reversely to each other, as indicated at 59 in Figs. 8 to 10, inclusive, and said faces are furthermore provided with the recesses 60. These dies are opened and closed by a lateral horizontal movement which is given to the pair of levers 61 62 in which the dies 95 are mounted, and these levers are actuated by an intermediate cam 63. The levers are peculiarly supported, so as to be capable of a lateral motion with respect to each in order to open and close the dies 42 43 and also of 100 a movement in a path at right angles to such lateral movement, such last-mentioned movement of the die-carrying levers serving to advance and retract the dies 42 43 toward and from the set of gripper-dies 40 41, as graphically indicated by Figs. 8 to 10, inclusive.

The dies 42 43 are fitted in seats 64, which are provided at the upper ends of the levers, and said dies are clamped in place adjustably by the plates 65, which are secured to the 105 levers by the bolts 66. The levers are provided below the dies with the openings 67^a, the same being contracted at the middle portion and curved, as more clearly represented by Fig. 6, and through these openings of the 110 die-carrying levers pass the stationary arbors 67, the latter having the threaded ends 68, which are screwed into the die-block 30. The levers are held from displacement by the nuts 69, which are screwed on the outer ends of 115 the arbors and are arranged to bear against the lateral faces of the levers. It will thus be understood that the levers are loosely-mounted on the arbors, so as to partake of the lateral motion and of a rocking motion, and 120 this lateral motion is imparted to the levers by the cam 63, the latter being secured to the main shaft 9 at a point adjacent to the gripper-actuating cam 56. (See Fig. 2.) The cam 63 acts against the trundle-rollers 70, 125 which are loosely mounted on the lower ends of said levers, and these rollers are held normally in engagement with the cam by a coiled spring 71^a, which is attached to the lower por-

- tions of the levers above the main shaft. (See Fig. 4.) The opening and closing movement of the dies under the action of the cam 63 causes the beveled faces 59 of said dies to 5 compress the wire and to form the points of the nails or tacks, and I will therefore designate the cam 63 as the "pointing-cam" in order to more readily distinguish it from the other cams which are carried by the main shaft.
- 10 The dies 42 43, are not curved or cut away at their opposing active faces, because they are merely beveled, and the curved recesses 60 in the rear side of the dies allow ample clearance therein for the heads of the nails.
- 15 The rocking or vibrating motion which the levers 61 62 are capable of upon the arbors 67 moves the set of dies 42 43 in a contrary or reverse direction to the line of feed of the wire through the machine, and this rocking 20 motion of the levers and the dies takes place when the set of dies 42 43 and the set of dies 40 41 are gripped firmly upon the wire, whereby the wire is held securely between the dies 40 41 and the wire is upset between 25 the two sets of dies in order to form the heads on the nails or tacks of the string or strip.

Positive means are provided in the machine for imparting the to-and-fro or rocking motion to the set of pointing and heading dies 30 42 43, and in one embodiment of this means I employ the heading-lever 71, which is acted upon by the heading-cam 72 and has operative connection with the die-carrying levers 61 62. The operative connection between 35 these parts is obtained by means of the arms 73, which are secured firmly by the screws 74 to the die-carrying levers 61 62, and these arms are fastened to the header-lever 71 by a transverse bolt 75. The lever 71 is fulcrumed 40 at a point intermediate of its length by means of the bolts 76, which are supported in an adjustable block 77, that is secured on the bed by a bolt 78, and to the lower end of this lever 71 is loosely fitted a trundle-roller 79, 45 which is adapted to ride against the active face of the header-cam 72.

A hook-bolt 80 is secured to the lower end of the header-lever, and it engages with a coiled spring 81, which is fastened to the lower 50 portion of the feeder-lever 28, as shown by Fig. 2. This spring serves to draw the header-lever and the feeder-lever toward each other and to keep the trundle-rollers 33 79 on said levers in engagement with the active faces 55 on the feeder-cam 34 and the header-cam 72.

The pointing and heading dies 42 43 may be adjusted in their seats of the header-levers by the set-screws 83. (See Fig. 4.)

The operation may be described as follows:

- 60 The action of the feeder-cam 34 on the feeder-lever moves the upper end of the latter toward the set of gripping-dies, and on this movement of said lever the plate 35 and the finger 36 coöperate to firmly grip the wire and 65 to advance the latter a distance exceeding the length of the nail or tack which is about to be formed, said movement of the lever draw-

ing the wire from the reel 14 and pushing it through the sets of dies and the opening or passage 84 in the upper end of the header-lever 71. During the feed of the wire the cams 56 63 maintain the two sets of dies in the open position shown by Fig. 8 and the header-cam 72 acts on the header-lever to retract the upper end thereof, and to thereby 70 rock the die-carrying levers 61 62 on their arbors 67, so as to maintain the set of dies 42 43 in retracted relation to the set of gripper-dies 40 41. Immediately following the advancement of the wire, as described, the 80 cam 56 closes the set of gripper-dies 42 43, as graphically indicated by Fig. 9. The wire being firmly held in place between the two dies 40 41 and being firmly gripped by the other set of dies, 42 43, the cam 72 becomes 85 active to throw the header-lever 71 and the die-carrying levers 61 62 toward the die-block 30, and thus the set of dies 42 43 are moved positively toward the companion set of dies 40 41, so that the parts assume the position 90 shown by Fig. 10. The closing of the dies 42 43 upon the wire by the action of the cam 63 makes the beveled faces 59 of said dies compress the wire, and thereby form the point on the nail or tack. The rocking motion imparted to the die-carrying levers by the header-lever takes place at the time when the wire is firmly gripped by the dies 40 41 and while the dies 42 43 are gripped on the wire, and this movement of said dies 42 43 carries the 100 wire toward the dies 40 41, and thereby forms the head on the nail or tack, as shown by Fig. 10. The movement of the dies 42 43 toward the gripper-dies is limited by the collars 85, which are fitted on the arbors 67, said collars 105 being removable and interchangeable with collars of different thicknesses, so as to determine the size of the nail-heads. Immediately following the pointing and heading of the nail the two sets of dies are opened simultaneously, the dies 42 43 are retracted by the pull of the spring 81 on the header-lever, and the feeder-lever 28 is operated on by the cam 34, so as to again advance or feed a proper 110 length of the wire. These operations are continued indefinitely and automatically for the rapid and economical manufacture of a string or strip of nails.

Changes within the scope of the appended claims may be made in the form and proportion of some of the parts, while their essential features are retained and the spirit of the invention is embodied. Hence I do not desire to be limited to the precise form of all the parts as shown, reserving the right to 115 vary therefrom.

Having thus described my invention, what I claim as new is—

1. In a nail-making machine, a pair of gripper-dies adapted to open and close upon the 120 wire, cam-operated levers mounted to move transversely of the path of the wire, a pair of combined pointing and heading dies having reversely-beveled faces mounted on said

levers adjacent to the gripper-dies, said levers being mounted to have a transverse motion and also a longitudinal motion toward and from the gripper-dies, means for causing said heading and pointing dies to close upon said wire and compress the same to form a point, and means for thereafter rocking the levers carrying said dies toward the clamping-dies, whereby to form a head on the next nail, substantially as described.

2. In a nail-making machine, a pair of gripper-dies adapted to open and close upon the wire, cam-operated levers mounted to move transversely of the path of the wire, a pair of combined pointing and heading dies having reversely-beveled faces mounted on said levers adjacent to the gripper-dies, said levers being mounted to have a transverse motion and also a longitudinal motion toward and from the gripper-dies, means for causing said heading and pointing dies to close upon said wire and compress the same to form a point, means for thereafter rocking the levers carrying said dies toward the clamping - dies, whereby to form a head on the next nail, and a stop carried between the two pairs of levers, whereby to limit the motion of one pair toward the other to regulate the thickness of the head.

3. In a nail-making machine of the class described, the combination with a set of gripper-dies, means for opening and closing the same, and a feed mechanism, of a pair of rocking levers normally held in operative relation to an interposed cam, a set of pointing-dies mounted in said levers and having the coöperative faces thereof beveled or inclined reversely, a header-lever having operative connection with said die-carrying levers, and a cam for vibrating the header-lever, substantially as and for the purposes set forth.

4. In a nail-making machine, the combination of a pair of gripper-dies, means for closing them upon the wire from which the nails are made transversely of the latter, a pair of arbors projecting parallel to the wire from the sides of the block carrying the gripper-dies, a pair of levers fulcrumed at an intermediate point thereof on said arbors, the fulcrums of said levers being interiorly convex, whereby to permit the longitudinal rocking movement to said levers toward and from said gripper-dies, a pair of combined heading and pointing dies carried by said last-named levers, means for forcing the lower ends of said levers apart, whereby to cause said heading and pointing dies to grip the wire and compress the same to form a point, and means to

rock said levers toward the gripper-dies to form a head on the next adjacent nail.

5. In a nail-making machine of the class described, the combination with a set of gripper-dies, and means for opening and closing the same, of a feeder-lever actuated by a cam and provided with means for advancing a wire, a pair of die-carrying levers opened and closed by a cam, a set of pointing-dies mounted in said die-carrying levers, a header-lever connected with said die-carrying levers and also actuated by a cam, and a spring connecting the header-lever and the feeder-lever, substantially as described.

6. A nail-making machine for making a string of nails from a single piece of wire comprising a feeding device consisting of a lever having a gripping means thereon and adapted to rock back and forth longitudinally to feed the wire at each forward movement the length of a nail, a guide-block through which the wire passes, a pair of gripper - dies, one mounted in a stationary block and the other having a reciprocating movement transversely of the wire, a lever mounted at an intermediate point thereof and adjustably connected to reciprocate said last-named die, a pair of longitudinal arbors fixed in the die-block of the gripper-dies and projecting rearwardly thereof, a pair of levers mounted at an intermediate point upon said arbors and having convexly-rounded bearings, whereby they may receive a longitudinal rocking motion, a pair of combined heading and pointing dies carried by said levers and adapted to grip, compress and upset the wire to form a point and head thereon, a heading-lever mounted on a transverse axis rearwardly of said last-named levers and connected therewith by a link, means for adjusting the forward throw of said heading-lever and dies to regulate the thickness of the head, an operating-shaft longitudinal of the machine, and cams mounted on said shaft, whereby to reciprocate said feeder-lever, oscillate said gripper-lever, force apart the lower ends of the pair of levers carrying the heading and pointing dies to form a nail-point and move forward the upper end of the heading-lever, whereby to press the heading-dies toward the gripper-dies and form a head on the next adjacent nail.

In witness whereof I have hereunto set my hand in the presence of two witnesses.

STANISLAS BEAUREGARD.
